UNITED STATES PATENT OFFICE.

FREDERICK C. RUFF, OF LOS ANGELES, CALIFORNIA, ASSIGNOR TO BY-PRODUCTS MANUFACTURING COMPANY, OF SAN FRANCISCO, CALIFORNIA, A CORPORATION OF CALIFORNIA.

PURIFYING GASOLENE FRACTIONS CONTAINING AROMATIC HYDROCARBONS.

1,263,289.

Specification of Letters Patent. Patented Apr. 16, 1918.

No Drawing.

Application filed January 15, 1917. Serial No. 142,540.

To all whom it may concern:

Be it known that I, FREDERICK C. RUFF, a subject of the Emperor of Germany, residing at Los Angeles, in the county of Los Angeles and State of California, have invented new and useful Improvements in Purifying Gasolene Fractions Containing Aromatic Hydrocarbons, of which the following is a specification.

10 In refining mineral oils, sulfuric acid of sufficient strength, applied in sufficient quantity and at a sufficiently high temperature, is used for the purpose of eliminating unsaturated hydrocarbons. For example, in 15 refining kerosene, fuming sulfuric acid is successfully used. Some mineral oils contain in their gasolene fraction such a proportion of toluene as to render it profitable to recover the same therefrom. This toluene 20 can, by a nitrating process, be successfully recovered as a nitrated compound. But in this case, likewise, in order to carry out the nitrating process successfully and economically, the unsaturated aliphatic hydrocarbons have to be first removed. But the unsaturated aliphatic hydrocarbons form so 25 small a proportion of the entire gasolene-toluene fraction and the difference in their densities is so great that a large amount of acid has to be used to insure a thorough mixture by agitation. If the acid used be fuming sulfuric acid, it will be found that a 30 large percentage of the toluene has been eliminated, since toluene, as well as unsaturated hydrocarbons, is soluble in fuming sulfuric acid. It might have been supposed 35 that this difficulty would be overcome by employing weak sulfuric acid, which will dissolve the unsaturated hydrocarbons without 40 dissolving also a part of the toluene, but the weak sulfuric acid will not attack the unsaturated hydrocarbons readily enough to secure satisfactory results.

By adding a small amount of nitric acid, 45 from 0.25% to 0.75%, to sulfuric acid (64° to 66° Baumé) I have found, however, that I can effect the almost complete elimination of the unsaturated hydrocarbons, while at the same time only traces of toluene are lost 50 in refining.

In nitrating the gasolene-toluene fraction refined by the above method, a smaller quantity of a mixture of sulfuric and nitric acids has to be applied, and the resulting tri-nitro-toluene is of a purer quality than when sulfuric acid alone is used in order to eliminate the unsaturated aliphatic hydrocarbons. The expense is small because the unsaturated hydrocarbons have been eliminated by a comparatively weak sulfuric acid which is comparatively cheap and contains only a small amount of nitric acid. The nitration itself is a safe operation because the unsaturated hydrocarbons have been eliminated. These unsaturated hydrocarbons have a great affinity for nitric acid, and tend to cause violent instantaneous reactions.

I claim:—

1. The process of removing unsaturated aliphatic hydrocarbons from gasolene fractions containing an aromatic hydrocarbon, which consists in adding to the gasolene fraction sulfuric acid containing nitric acid 70 to the extent of not more than one per cent. of the sulfuric acid.

2. The process of removing unsaturated aliphatic hydrocarbons from gasolene fractions containing an aromatic hydrocarbon, which consists in adding to the gasolene fraction sulfuric acid containing nitric acid 80 in an amount insufficient to materially attack the aromatic hydrocarbon contained in the gasolene fraction.

3. The process of removing unsaturated aliphatic hydrocarbons from light oil containing an aromatic hydrocarbon, which consists in adding to the light oil sulfuric acid containing nitric acid in the extent of not more than one per cent. of the sulfuric acid.

4. The process of removing unsaturated aliphatic hydrocarbons from light oil containing an aromatic hydrocarbon, which consists in adding to the light oil sulfuric acid containing nitric acid in an amount insufficient to materially attack the aromatic hydrocarbon contained in the light oil.

FREDERICK C. RUFF.
